UNITED STATES PATENT OFFICE.

CHARLES L. HOPKINS, OF RIVER FOREST, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL SWITCH.

Application filed September 25, 1919. Serial No. 326,115.

To all whom it may concern:

Be it known that I, CHARLES L. HOPKINS, a citizen of the United States, residing at River Forest, in the county of Cook and State of Illinois, have invented new and useful Improvements in Electrical Switches, of which the following is a full, clear, concise, and exact description, reference being had to the accompanying drawing, forming a part of this specification.

My invention relates to electrical switches and more specifically to pull switch sockets.

One of the objects of my invention is to provide an improved switch construction in which the circuit is simultaneously broken at two points, whereby the arcing effect is divided, and the danger of injury to the switch is lessened.

Further objects will appear from the detailed description to follow and from the appended claims.

In the drawings in which one embodiment of my invention is shown

Fig. 1 is a plan view of a pull switch socket embodying my invention, the cap being removed;

Fig. 2 is a section substantially on the line 2—2 of Fig. 1;

Fig. 3 is a section substantially on the line 3—3 of Fig. 1;

Fig. 4 is a section substantially on the line 4—4 of Fig. 2;

Fig. 5 is a section substantially on the line 5—5 of Fig. 1;

Fig. 6 is a section substantially on the line 6—6 of Fig. 1;

Fig. 7 is a section substantially on the line 7—7 of Fig. 1;

Fig. 8 is a detail perspective view of one of the rotatable contacts; and

Fig. 9 is a detail perspective view of a part of the switch mechanism.

In order to give a general idea of the invention, it is here stated that the embodiment of my invention here shown comprises a pull switch socket having a pair of rotatably mounted contacts 10 and 11 (which, however, are always electrically connected with each other), a pair of spring contact fingers 12 and 13 (insulated from each other in the "off" position of the switch and with respect to which the rotatably mounted contacts 10 and 11 respectively snap into and out of engagement in their rotation), wiring terminals 14 and 15 (the wiring terminal 14 being electrically connected with the spring contact finger 12 and the wiring terminal 15 being electrically connected with the threaded shell contact 16 of the receptacle), a center contact 17 for the receptacle, electrically connected with the spring contact finger 13 (Fig. 5), an insulating base 18 on which the receptacle contacts, wiring terminals and switch mechanism are mounted, and a sheet metal casing 19 for housing the insulating base 18 and the parts supported thereby.

From the construction described, it will be seen that the spring contact fingers 12 and 13 are insulated from each other in the "off" position of the switch, that the spring contact finger 12 is always electrically connected with the wiring terminal 14 and that the spring contact finger 13 is always electrically connected with the center contact 17. It will also be seen that as the movable contacts 10 and 11 are rotated, the circuit between the wiring terminal 14 and center contact 17 will be simultaneously broken at two points, thereby dividing the arc and lessening the danger to the switch mechanism, and preventing other undesirable effects.

Referring to the construction in detail, the switch mechanism is located in a recess 20 in the insulating base 18. This switch mechanism comprises, in addition to the rotatably mounted contacts 10 and 11, and the cooperating spring contact fingers 12 and 13, previously described, a rotatably mounted contact carrier 21 of insulating material, an oscillatable switch lever or drum 22 for operating the contact carrier 21, a ratchet connection 23 between the switch lever 22 and the contact carrier 21, a coil torsion spring 24 for returning the switch lever 22 after it has been operated by the pull chain 25 and a U-shaped switch frame 26 on which the contact carrier 21 and switch lever 22 are mounted, and which switch frame forms a part of an electrical circuit between the two contacts 10 and 11 (which as previously stated are always in electrical connection with each other).

The contact carrier 21 comprises two similar ratchet-shaped portions 27, on which the contacts 10 and 11 are mounted, these contacts being located at opposite sides of a

central circular web 28 which serves as a barrier to prevent short circuiting. The contact 10 has a spiral contact portion which rests on top of a corresponding spiral portion 5 of the ratchet-shaped part 27 of the contact carrier, and is provided with an inwardly extending arm 29 (Fig. 8) having a collar portion 30, into which a boss 31, formed integral with the contact carrier 21, 10 extends, the collar 30 and arm 29 thus serving to hold the contact 10 in position on the brush carrier.

To further assist in holding the contact in position on the carrier, and position it on the carrier, the contact has an inwardly extending projection 32 (Fig. 8) which engages a corresponding recess in the carrier. The collar 30 forms a journal for the carrier as it extends into an opening in the standard 20 and 33 of the switch frame 20. The arm 29 not only serves to hold the contact in position, but also electrically connects it with the switch frame 26.

The switch lever 22 comprises a central supporting spider 34 (Fig. 9) on which are sleeved three insulating discs 35, 36 and 37, and an insulating sleeve 38 located between the discs 36 and 37. The central web portion 39 of the spider 34 forms one member 30 of the ratchet connection between the switch lever 22 and the contact carrier 21, this web portion being provided with shoulder portions 41 for engagement with ratchet teeth 41, struck up from an inwardly extending arm 42 formed integral with the contact carrier 11 (Fig. 5). This arm 41 has an opening through which extends a switch shaft 43, which switch shaft may be molded in the contact carrier 21. The arm 42 of the contact thus serves to hold the contact in place on the ratchet-shaped portion of the contact carrier, the contact being provided also with an inwardly extending projection 44 (Fig. 5) to properly position it on the carrier.

The legs of the spider terminate in outwardly extending feet 45, which cooperate with outwardly extending projections 46 on the web portion of the spider to hold the insulating discs 35, 36 and 37 and the insulating sleeve 38 in position on the spider.

In assembling the lever, the legs of the spider are sprung inwardly enough to slip the discs 35 and 36, the sleeve 38 and the disc 37 over the feet 45, after which the legs are allowed to spring outwardly, so that the discs and sleeve are held in place between the outwardly extending projections 46 and the feet 45. The legs of the spider rotatably engage a cup-shaped sheet metal bearing member 47, this bearing member having a reduced collar portion 48 which extends into an opening in an upright 49 on the switch frame. The shaft 43 extends into 60 this collar portion 48 and is supported

thereby. One end of the coil torsion spring 44 is secured to the web 39 of the spider and the other end of this spring is secured to the upright 49 of the switch frame 26.

The contact 11 is always electrically connected with the switch frame 26 (and thus with the other contact 10) through its inwardly extending arm 42 and through the spider 34 on the shaft 43 and the bearing member 47. The switch frame is secured to the insulating base 18 by means of a screw 30. As previously stated, the spring contact finger 13 is always in electrical connection with the center contact 17, this connection being effected by means of a screw 51 (Figs. 1 and 5) which also serves to hold this spring contact finger and the center contact in place on the base 18.

The wiring terminal 14, as previously stated, is electrically connected with the spring contact finger 12, this wiring terminal being held in position on the base 18 and in engagement with the spring contact finger 12 by means of a screw 52. Each of the wiring terminals 14 and 15 are provided with the usual binding screw 53.

As previously stated, the wiring terminal 15 is electrically connected with the threaded shell contact 16 of the receptacle, this connection being effected by means of a screw 54 (Figs. 1 and 4), the head of which engages the flange 55 of the threaded shell contact, and the end of the screw 54 is threaded into the binding plate of the wiring terminal 15.

The chain 25 is secured to the switch lever 22 by means of a hook member 56 (Fig. 3) secured in place between the insulating discs 36 and 37. The oscillating movement of the switch lever is limited to substantially 180 degrees by means of a projection 57 formed integral with the insulating disc 37, which projection 57 engages suitable abutments 58 and 59 on the insulating base 18 to limit the movement of the switch lever in each direction.

The circuit from the wiring terminal 14 to the wiring terminal 15 has been outlined in connection with the description of the construction, and is as follows: From the wiring terminal 14, through the spring contact finger 12, rotatable contact 10, brush arm 29, switch frame 26, bearing member 47, spider 34 (or shaft 43), arm 42, rotatable contact 11, spring contact finger 13, screw 51, and center contact 17 through whatever translating device is inserted in the receptacle to the threaded shell contact 16 and thence through the screw 54 to the wiring terminal 15.

As previously stated, when the switch is moved to "off" position, the circuit is simultaneously broken at two points between the center contact and the wiring terminal, thus dividing the arc.

The operation of my improved switch is as follows:

Assuming that the parts are in the position shown in Figs. 1, 2, 3, 5 and 6, (in which the switch is in "off" position) and it is desired to turn the switch "on," the pull chain 25 is pulled down, to move the switch lever through substantially 180 degrees. During this movement of the switch lever 10 through 180 degrees, the contact carrier 21 also is moved through 180 degrees through the ratchet mechanism 23. During this movement of the contact carrier 21, the spring contact fingers 12 and 13 ride upon 15 the ratchet portions 27 of the contact carrier and finally snap down into engagement with the contacts 10 and 11 respectively. This simultaneously makes the circuit between the center contact and wiring terminal at two 20 points.

When the pull chain 25 is released, the spring 24 returns the switch lever to its original position, the contact carrier, however, remaining stationary during this return 25 movement of the switch lever, the ratchet connection between the switch lever and contact carrier permitting this relative movement. The spring contact fingers 13 and 14 would prevent any return movement 30 of the carrier, by their engagement with the shoulders behind which they have just snapped. If now it is desired to turn the switch "off", the pull chain 25 is again operated, again causing the carrier 21 to be 35 moved through 180 degrees. During this movement of the carrier 21, the spring contact fingers 13 and 14 ride upon the contacts 10 and 11 and finally snap off from the rear end of these contacts. This breaks the 40 circuit simultaneously at two points between the center contact and its wiring terminal and divides the arc.

When the pull chain 25 is released, it and the switch lever are again restored to their original positions by means of the spring 45 24, the contact carrier 21 remaining stationary during this return movement. The spring contact fingers 13 and 14 would prevent any return movement of the carriers 50 by engagement with the shoulders behind which they have just slipped.

Having thus described my invention, what I claim as new and desire to secure by Letters Patent is:

55 1. A switch mechanism comprising a pair of contact fingers insulated from each other in the "off" position of the switch and located side by side; and means for establishing electrical connection between said contact fingers comprising a rotatable contact carrier; two contacts carried by said carrier and located side by side and movable into and out of engagement with said pair of contact fingers respectively; and a switch 60 frame of conducting material for support-

ing said carrier, both of said contacts being electrically connected to said switch frame.

2. A switch socket comprising a receptacle contact, a wiring terminal and a switch mechanism for controlling the circuit between said wiring terminal and said receptacle contact, comprising a pair of contact fingers insulated from each other in the "off" position of the switch and located side by side, one of said contact fingers being 70 electrically connected with the wiring terminal, and the other being electrically connected with the receptacle contact; and means for establishing electrical connection between said contact fingers comprising a rotatable contact carrier; a pair of contacts carried thereby; a ratchet mechanism for operating said contact carrier, and means for rotatably supporting said carrier, said supporting means electrically connecting 75 said contacts with each other.

3. A switch socket comprising a wiring terminal; a receptacle contact; a pair of contact fingers, one electrically connected with said receptacle contact and the other electrically connected with said wiring terminal, said contact fingers being insulated from each other in the "off" position of the switch; and means for establishing electrical connection between said contact fingers comprising a rotatable contact carrier having an insulating flange forming a barrier between said fingers, two contacts located thereon on opposite sides of said barrier, ratchet mechanism for operating 90 said contact carrier, and means external to said carrier for permanently connecting said rotatable contacts with each other.

4. A switch socket comprising shell and center receptacle contact members; wiring terminals therefor; switch mechanism for controlling the circuit between one of said wiring terminals and one of the receptacle contact members, said switch comprising a contact carrier; a pair of contacts thereon; a switch lever engaging said carrier; and a frame having bearings for supporting said carrier and switch lever, said contacts having portions extending to said bearings whereby said frame electrically connects 105 said contacts with each other.

5. A switch socket comprising an insulating base, receptacle contacts carried thereby, wiring terminals also carried by said base, and a switch mechanism also carried by said base, said switch mechanism comprising a stationary contact electrically connected with one of said wiring terminals, a second stationary contact electrically connected with one of said receptacle contacts, an insulating rotatable carrier, a switch frame having bearings for said carrier, a pair of rotatable contacts mounted on said carrier and arranged to engage said stationary contacts, one of said rotatable contacts 110 115 120 125 130

tacts having an extension forming a journal for supporting said carrier in said frame and electrically connecting said contact with said frame, a shaft for supporting said carrier, an operating member arranged to oscillate on said shaft, a spring surrounding said shaft for returning said operating member, ratchet connection between said

carrier and said oscillating member, and means surrounding said shaft for supporting said operating member, the other of said rotatable contacts being permanently electrically connected with said switch frame. 10

In witness whereof, I have hereunto subscribed my name.

CHARLES L. HOPKINS.
